No. 886,615.

PATENTED MAY 5, 1908.

O. LAUBER & N. KOCH.
PNEUMATIC RÉCUPERATOR FOR RECOIL GUNS.
APPLICATION FILED APR. 30, 1906.

UNITED STATES PATENT OFFICE.

OTTO LAUBER AND NORBERT KOCH, OF ESSEN-ON-THE-RUHR, GERMANY, ASSIGNEES TO FRIED. KRUPP AKTIENGESELLSCHAFT, OF ESSEN-ON-THE-RUHR, GERMANY.

PNEUMATIC RECUPERATOR FOR RECOIL-GUNS.

No. 886,615.

Specification of Letters Patent.

Patented May 5, 1908.

Application filed April 30, 1906. Serial No. 314,570.

To all whom it may concern:

Be it known that we, OTTO LAUBER, residing at Essen-on-the-Ruhr, West, Germany, and NORBERT KOCH, residing at Essen-on-the-Ruhr, Germany, both subjects of the Emperor of Germany, have invented a certain new and useful Improvement in Pneumatic Recuperators for Recoil-Guns, of which the following is a specification.

10 The present invention relates to the type of recoil-guns that is provided with a pneumatic recuperator comprising a displacer and a compressed air receptacle. In such pneumatic recuperators a piston, working in a cylinder, forces liquid from the cylinder into a compressed air receptacle during the recoil of the gun-barrel, the piston and the cylinder forming together the so-called displacer, and, after complete recoil, the compressed air 15 forces the liquid back to the displacer to cause the return of the gun-barrel through the medium of the displacer.

In the gun according to the present invention, the compressed air receptacle is of simple construction and capable of great resistance, the recoil-brake and the recuperator occupy but a small space, and the relative arrangement of the parts is selected in such a manner that the recoil-brake and the recuperator can be placed in and protected by 20 the cradle.

35 In the accompanying drawing, the invention is, by way of example, shown applied to a gun in which the recoil-brake is a fluid brake.

Figure 1 shows the parts of a gun to which our invention relates, partly in vertical longitudinal section and partly in elevation; Fig. 2 is a section on line 2—2, Fig. 1, looking 40 from the left; Fig. 3 is a section on line 3—3, Fig. 1, looking from the left; Fig. 4 is a section on line 4—4, Fig. 2, looking from above; and Figs. 5 and 6 are sections corresponding to those shown in Figs. 2 and 3 but of a 45 slightly different embodiment.

Referring first to the embodiment shown in Figs. 1 to 4, A is the gun-barrel which slides in the usual manner on the cradle B within which is placed both the fluid-brake 50 and the recuperator.

The fluid-brake is of usual construction and consists of the brake-cylinder C, the piston D and the piston rod D'. Grooves or channels (not shown in the drawing) are provided in the piston D or in the wall of the cyl-

inder to allow the brake-fluid to pass from one side of the piston to the other.

The recuperator consists mainly of the displacer cylinder E having piston F and piston-rod F', and a compressed air receptacle G in the form of a cylinder closed at one end and having an air space H'. The displacer cylinder E is integral with the brake cylinder C, the cylinders being made from a single piece of material, and the cylinders are provided with an integral annular screw-threaded flange H (Figs. 2 and 4) by means of which the two cylinders are screwed into the compressed air receptacle G. The receptacle G is rigidly connected to the horn a' of the breech of the gun-barrel, and the piston-rods D' and F' are screwed into a plate J which closes the cradle B towards the front.

The displacer cylinder E communicates with the compressed air receptacle G through the medium of a channel K (Figs. 2 to 4) having a passage k' leading to the displacer cylinder and a passage k² leading to the compressed air receptacle.

In the front part of the displacer cylinder E is arranged a check-valve M N (Figs. 1 and 4) having its valve body M held on the seat N by a spring P. The closed valve does not, however, entirely cut off the displacer cylinder, as passages n' of small diameter are provided in the valve seat N. The channel K and the part of the displacer cylinder E which is in front of the piston F is always filled with liquid, while the compressed air receptacle, when in the position of rest shown in Fig. 1, contains in addition to the compressed air such an amount of liquid that the passage k² of the channel K is immersed in liquid at any elevation of the gun-barrel, thereby preventing access of the compressed air to the stuffing box of the displacer cylinder.

When the gun-barrel is in the position of rest the several parts of the fluid brake and of the recuperator assume the relative position seen in Fig. 1. The compressed air receptacle G, and the brake-cylinder C and displacer cylinder E, which are rigidly secured to the receptacle G, take part in the recoil movement and return movement of the gun-barrel, while the piston-rods D' F' and pistons D F remain stationary due to their rigid connection with the cradle B.

The mode of operation of the fluid brake during the recoil and return movement has

no bearing on the present invention and, therefore, need not be explained.

During the recoil and return movement the recuperator works as follows: At the 5 start of the recoil the liquid, in front of the piston F and in the displacer cylinder E, opens the valve M and is forced into the receptacle G through the passage k' , the channel K and the passage k^2 , the compressed air 10 in the receptacle G being thereby further compressed. When the recoil-energy of the recoiling parts is exhausted, the compressed air expands and forces the liquid out from the receptacle G. As the check-valve M N is 15 closed when the liquid flows back, the liquid must pass into the displacer cylinder E through the narrow passages n' and the liquid is consequently throttled to a considerable extent and acts as a brake during the return 20 of the gun-barrel, the return being effected by the liquid forcing the displacer piston F back to its position of rest.

The embodiment shown in Figs. 5 and 6 differs from the one just described merely 25 in having two displacer cylinders E from which the liquid, on the recoil of the gun-barrel, is forced through two passages k' into a common channel K and from there into the

compressed air receptacle G. By means of this construction we obtain an absolutely 30 symmetrical arrangement of the several parts of the fluid-brake and of the recuperator.

Having described our invention, what we claim as new is:

1. In a recoil gun, a pneumatic recuperator comprising a receptacle for compressed air and a displacer arranged within said receptacle and communicating therewith, and a brake cylinder arranged within the compressed air receptacle. 35

2. In a recoil gun, the combination with the cradle, of a pneumatic recuperator arranged within the cradle and comprising a receptacle for compressed air and a displacer arranged within said receptacle and communicating therewith, and a brake cylinder arranged within the compressed air receptacle. 40 45

The foregoing specification signed at Düsseldorf, this fourteenth day of April, 1906. 50

OTTO LAUBER.
NORBERT KOCH.

In presence of—

ALFR. POHLMAYER,
PETER RIEBER.
